UNITED STATES PATENT OFFICE.

PIERRE JOSEPH CHÉRON, OF NEW YORK, N. Y., ASSIGNOR TO FERDINAND FUCHS, HENRY FUCHS, AND FREDERICK FUCHS, OF SAME PLACE.

DESIGN FOR A BORDER FOR SILVERWARE.

SPECIFICATION forming part of Design No. 27,255, dated June 29, 1897.

Application filed April 17, 1897. Serial No. 633,405. Term of patent 3½ years.

To all whom it may concern:

Be it known that I, PIERRE JOSEPH CHÉRON, a citizen of the United States, residing at New York city, in the county and State of New York, have invented and produced a new and original Design for Borders on Silverware, of which the following is a specification, reference being had to the accompanying drawing.

The drawing is an elevation of the border design for silverware, and which is especially intended for larger pieces, such as bowls, plates, tureens, pitchers, &c.

The leading feature of my design consists in a raised scalloped surface forming a border on the articles, such as plates, trays, fruit-bowls, and other like articles.

The design is composed of a series of thistle

buds and blossoms represented in various positions with an outer scroll or fancy scallop work. The thistles at the right, as shown in ²⁰ the drawing, are in the form of buds A. Those next in order are still larger buds B, almost in bloom, after which come smaller buds C and full blossoms D. Outside of the buds and twining with them I place fancy ²⁵ scallop-work E as an outer finish.

What I claim is—

The design for a border for silverware substantially as described and shown.

PIERRE JOSEPH CHÉRON.
